BEDSPRING HOISTING MEANS

Eugene Umbach, Brooklyn, N. Y., assignor to
 Sleepwell Metal Bed Co. Inc., Brooklyn, N. Y., a
 corporation of New York

Application January 3, 1934, Serial No. 795,139

5 Claims. (Cl. 5—323)

This invention relates to an improved structural means to facilitate hoisting and holding of a bed spring in an elevated position clear of the bed frame to facilitate sweeping or cleaning the floor and cleaning of the bed frame and spring itself.

It is admittedly old in this particular line of endeavor to provide manually controlled mechanical means to expedite the handling and hoisting of a bed spring, a box spring mattress or the like. It follows, therefore, that the purpose of the present invention is to provide a novel structural assemblage characterized by certain appreciable structural differences and refinements permitting the desired result to be accomplished in a more satisfactory and dependable manner.

Of chief importance is the idea and adaptation means whereby the spring is liftable to inclined position, the means being such as to permit this result to be accomplished in an alternative manner, that is allowing one longitudinal edge portion of the spring to be lifted first and cleaned and then lowered while the opposite edge portion is lifted to a corresponding position for cleaning.

A further feature of construction is predicated upon the selection and use of a duplex arrangement of stay linkage devices having accompanying adapter units serving as attaching or hanger means and permitting installation of the device on conventional bed frames.

Other and more specific features of the invention will become more readily apparent from the following description and drawings.

35 In the drawings:

Figure 1 is a view in section end elevation showing the side or longitudinal rails of the bed frame, a conventional mattress supporting spring, and the structurally coordinated improvements constituting the novelty of the present invention.

Figure 2 is a view similar to Figure 1 showing how the invention operates this view showing portions broken away to illustrate both sets of the devices.

Figure 3 is a diagrammatic view partially in elevation illustrating a top plan version of the principal features of the invention.

Figure 4 is an enlarged elevational view of a fragmentary nature depicting the particular formation of the jointed end of the companion links of one of the stay devices.

Figure 5 is a view of Figure 4 looking at it in a direction from left to right.

55 It is believed that so far as the general as-

sembly is concerned it is best shown in Figure 2. Therefore by referring to Figure 2 it will be noted that the longitudinal side rails of the bed frame are denoted by the numerals 6. The bed spring, which is of a conventional style is differentiated, as a unit, by the numeral 7. As is customary the bed spring embodies a base frame and the bars of this frame are distinguished by the numerals 8. They are here shown as of angle formation and correspond in cross section with the frame rails. The cross braces, forming a part of the bed spring are denoted by the numerals 9 and it will be observed in Figure 2 that the hoisting and stay devices 10 are connectible to the central ones of said braces 9. Both of these devices 10 are duplicate in construction and a description of one will suffice for both. It is to be explained however that they are alternately operable and located to perform successively, whereby to permit one side or half portion of the bed spring to be lifted up in tilted position for cleaning and then lowered and the other side then lifted and cleaned in an obvious manner. It is to be further observed that there are two adapter units 11 and these are also duplicate and serve to accommodate respective hoisting or stay devices 10. Each adapter unit is, as the name implies fashioned to accommodate the bed frame and bed spring. It is preferably formed of appropriate strength and may be said to be of general U-shaped form. The central or connective portion 12 is twisted to assume a substantially vertical position. The upstanding end portions may be said to be of L-shaped form as indicated at 13 with their terminals suspended from the rails 6. It is to be observed however that the extreme free ends of the L-shaped terminals which may be distinguished as the extremities 14 rise above the rails and function as stop devices to keep the bed spring from slipping off when it is in an inclined position as shown in Figure 2.

The hoisting and stay devices 10 have a toggle-like action and not only serve to support the bed spring 7 in an inclined position but facilitate lifting it as it is started and pulled upwardly by the attendant. Each device 10 comprises what may be designated as a lower link 15 and companion upper link 16. The upper link is pivoted at its outer end as at 17 to the cross brace 9. The corresponding end of the lower link 15 is pivoted as at 18 to the metal strap 12. The adjacent or corresponding inner ends of the links are pivoted together.

This is shown better in Figure 4. Referring to this figure it will be observed that the inner end of the link 15 is directed at right angles or laterally as denoted at 19. At its free end it is provided with a stud 20 (see Figure 5) which serves not only as a stop element but also as a means for attaching a handle or hand grip 21 to said link 15. The link 16 also has its inner end bent laterally as indicated at 22 and pivotally connected as at 23 to the link 15 at a point inwardly of the part 19. This allows the jointed end portions of the two links to swing into intersecting relationship and beyond "dead center" so as to provide a substantially automatic self sustaining stay means. Stated otherwise when the two links are expanded to the sustaining position shown in Figure 2 the pivoted end of the link 16 swings across the corresponding bent end portion 19 of the link 15 and said link 16 rests against the stop pin or stud 20. To aid in the sensitivity and nicety of operation I provide coil springs 24 and 25 connected to the links 15 and 16 and the parts 9 and 12 respectively as shown in Figure 2. These springs exert a stress or pull upon the links to facilitate unfolding or opening of the links and as the links unfold and spread apart they exert an upward stress or thrust upon the bed spring to aid in lifting it. Initially however the bed spring is grasped at about the center by the attendant. It is lifted upwardly and the opposite edge portions fulcrum against the stop elements 14 as shown in Figure 2.

Assuming that the bed spring is inclined to the position shown in Figure 2 and it is desired to lower it, it is obvious that this is accomplished by grasping a hold of the handle or hand grip 21 and forcing in a direction away from the attendant. This breaks the joint so to speak and allows the bed spring to be lowered to its original horizontal plane. As before stated the use of the two units 11 and the complementary stay devices 10 and the arrangement thereof on alternate opposite sides of the bed frame permits the bed spring to be lifted up first on one side and then on the other to facilitate cleaning of the spring, cleaning of the bed frame and slats, if any, and the floor therebeneath.

Having thus described my invention, what I claim as new is:

1. In a structure of the class described, a stay device comprising a pair of links, the inner end of one link being directed laterally and provided with a stud constituting a stop element with the corresponding end of the remaining link being directed laterally and pivotally attached to said first named link, the two laterally extending portions projecting in the same direction and the lateral part of said remaining link being pivoted to the other link an appreciable distance from the lateral part of said other link and the stud being engaged by a part of said remaining link when the links are in unfolded position, and means for connecting the outer ends of the links with a bed frame and bed spring respectively, together with a hand grip carried by said stud to facilitate operating the links.

70

2. In a structure of the class described, a pair of links having their inner ends bent at right angles, the bent end of one link being pivoted to the other link an appreciable distance from the bent end of said other link, a stud on the bent end of said other link for engagement by the first link for limiting unfolding movement of the links, a cross member adapted to be supported by a part of a bed and to which the outer end of the stud carrying link is pivoted, means for pivoting the outer end of the other link to a bed spring assembly, and a spring for connecting each link to the part to which the outer end of the link is pivoted.

3. In combination with a bed and its spring assembly, a pair of cross bars having their ends extending upwardly and the upper end of each end being bent outwardly at right angles to rest on a part of a bed and the extremity of this part being bent upwardly to provide a stop for an edge portion of the spring assembly, links connecting the bars to the spring assembly, each link being formed of two sections having their inner ends bent at right angles, the bent end of one section being pivoted to the other section an appreciable distance from the bent end of said other section, a stud on the bent end of said other section for engagement by the first section for limiting unfolding movement of the sections, and the outer end of the stud carrying section being pivoted to a bar and the outer end of the other section being pivoted to the spring assembly.

4. In a structure of the class described, a stay device comprising a pair of links, the inner end of one link being directed laterally and provided with a stop element, with the corresponding end of the remaining link being directed laterally and pivotally attached to said first named link, the two laterally extending portions projecting in substantially the same direction and the lateral part of said remaining link being pivoted to the other link an appreciable distance from the lateral part of said other link and the stop element being engaged by a part of said remaining link when the links are in unfolded position, and means for connecting the outer ends of the links with a bed frame and bed spring respectively.

5. In a structure of the class described, a stay device comprising a pair of links, the inner end of one link being directed laterally and provided with a stop element, with the corresponding end of the remaining link being directed laterally and pivotally attached to said first named link, the two laterally extending portions projecting in substantially the same direction and the lateral part of said remaining link being pivoted to the other link an appreciable distance from the lateral part of said other link and the stop element being engaged by a part of said remaining link when the links are in unfolded position, means for connecting the outer ends of the links with a bed frame and bed spring respectively, and a spring connected at one end to one of said links and at the other end to the part of the bed to which said link is connected.

EUGENE UMBACH.
